ATTORNEY

UNITED STATES PATENT OFFICE.

AUGUST LEO, OF EUREKA, CALIFORNIA.

WRENCH.

1,262,682.

Specification of Letters Patent. Patented Apr. 16, 1918.

Application filed September 20, 1916. Serial No. 121,240.

To all whom it may concern:

Be it known that I, AUGUST LEO, a subject of the Czar of Russia, residing at Eureka, in the county of Humboldt and State 5 of California, have invented certain new and useful Improvements in Wrenches, of which the following is a specification.

This invention relates to wrenches, and particularly to wrenches of the threaded 10 handle bar type.

The primary object of the invention is to provide a wrench of the type wherein improved means is employed for mounting the various movable parts in the wrench proper, 15 wherein the various parts are prevented from becoming deranged, broken or jammed when in use, wherein the movement of the jaws both inwardly and outwardly of the shank is positive, and wherein the wrench 20 may be quickly, easily and with but little effort adjusted properly.

With these objects in view, together with others which will appear as the description proceeds, the invention resides in the novel 25 formation, combination and arrangement of parts, all as will be described more fully hereinafter, illustrated in the drawings, and particularly pointed out in the claim.

In the drawings:—

30 Figure 1 is a side elevation, parts broken away, of a wrench constructed in accordance with the invention;

Fig. 2 is a longitudinal sectional view taken through the improved wrench;

35 Fig. 3 is a sectional view taken on line 3—3 of Fig. 2 and looking in the direction indicated by the arrows; and

Fig. 4 is a similar view taken on line 4—4 of Fig. 2 and looking in the direction indicated by the arrows.

Referring now to the drawings, 5 indicates the wrench shank, and is formed at one end with oppositely extending jaw portions 6 and 7, and the shank is reduced and 45 rounded for the major portion of its length and inwardly from its opposite end as shown. A head 8 is formed at the lower end of the shank 5, and the said shank is grooved as at 9 adjacent the juncture of the head 50 with the reduced shank portion. The shank 5 is provided with a centrally arranged slot 10, the latter extending from adjacent the headed end of the shank through and to the opposite end of the same. This slot extends 55 diametrically through the reduced portion of the shank 5, and the stem portion 11 of

a sliding member is arranged within the said slot so as to move longitudinally thereof. This stem is provided at its outermost end with an enlargement, the same constituting 60 oppositely disposed jaw portions 12 and 13, for co-operation with the jaw portions 6 and 7 respectively of the shank 5. The edges of the shank or stem 11 which protrude beyond the ends of the slot 10 are provided with inclined teeth 14, adapted to be engaged by teeth 15 projecting from the inner periphery of a rotating grip or sleeve 16 inclosing the lower portion of the shank 5.

The upper ends of this sleeve fit within an 70 annular shoulder formed upon the shank 5 adjacent the juncture of the larger with the smaller portions thereof. To hold the sleeve 16 upon the shank, a pin 17 is driven through the same, and the medial portion of 75 the pin rests within the groove 9 formed at the juncture of the head 8 with the reduced portion of the shank 5 of the wrench. A set screw 18 is threaded through the reduced portion of the shank 5, and engages at its 80 inner end within a slot 19 disposed longitudinally of the stem 11. This screw limits the outward movement of the movable jaw and prevents the device from becoming accidentally dismembered.

The portions constituting the jaws 7 and 85 13 are serrated upon their adjacent faces as at 20, whereby a pipe gripping portion is provided.

From this construction, it is apparent that 90 I have provided an extremely simple and yet thoroughly practical sliding jaw wrench. When the various parts have been assembled, it is obvious that rotation of the grip or sleeve 16 in one direction will cause the stem 95 11 to move outwardly of the shank 5, and reverse rotation of the sleeve will force the stem inwardly. The sleeve is held in positive connection with the shank 5, and yet is capable of rotating freely thereon. It will 100 be understood, of course, that the teeth 14 and 15 upon the stem and sleeve respectively are always intermeshed, so that the device will instantly operate upon rotary movement being delivered to the sleeve.

While the present disclosure is that of the preferred embodiment of the invention, it is obvious that various changes in the minor details of construction and arrangement of parts may be resorted to, if desired, without departing from the spirit of the invention or the scope of the claim, and the right to 105

make such variation in construction is hereby reserved.

What is claimed is:—

In a wrench, a shank having a central longitudinal slot, one end of said shank being cylindrical and of reduced size, the said reduced end being provided with an annular groove, a rotatable sleeve inclosing said shank, a pin extending through said sleeve 5 and resting in said groove, a stem arranged within said slot and being capable of sliding longitudinally therein, the edges of said

stem projecting beyond said slot, threads on said edges, a short thread upon the interior of said sleeve engaging said stem threads, 15 the said stem having a longitudinal groove, and a screw extending through said shank and engaging in said groove.

In testimony whereof I affix my signature in presence of two witnesses.

AUGUST LEO.
